DAVID E. ANDERSON, OF DETROIT, MICHIGAN

CRANK-CASE VENTILATING SYSTEM

Application filed December 27, 1927. Serial No. 242,584.

This invention relates to an arrangement for ventilating the crankcase of an internal combustion engine to withdraw water-vapor, gasoline fumes and other products of combustion which escape past the piston rings and enter the crankcase. If left to condense, these particles unite with the engine oil, destroying its lubricating properties. It is desirable that the crankcase fumes be returned to the engine 10 cylinders for when discharged into the atmosphere, they are likely to find their way into the vehicle body and cause discomfort to the passengers. When the fumes are led into the carburetor air intake, it is apparent 15 that at high engine speeds the suction will be so great that a considerable volume of gases will be withdrawn from the crankcase and, owing to the speed flow, oil particles are likely to be entrained with the gases and enter 20 the carburetor. Here they would collect upon the delicate adjusting mechanisms, or settle in the fine-bored fuel passages and in time interfere with the action of the carburetor. To prevent this difficulty, I have devised an arrangement in which the flow of vapors from 25 the crankcase is reduced at high engine speeds or when the engine fuel consumption is large, as when it is operating under heavy load. This, I accomplish by a connection between 30 the usual throttle valve and the valve provided in the conduit connecting the crankcase with the carburetor air intake passage. The connection is preferably such that the flow thru the last-named passage is restricted in 35 an increasing amount as the throttle valve is opened.

I have illustrated my preferred construction in the somewhat diagrammatic view shown on the drawing. I have preferred to 40 use, for purposes of illustration, a Cadillac V-8 engine and the figure is, in part, a vertical section thru the center of the V. The reference character 2 indicates a portion of the crankcase of internal combustion engine.

45 The crankcase is provided with a breather opening, 4, illustrated as of conventional type although, if preferred, a breather equipped with an air filter or cleaner may be used instead to insure that nothing but clean air enters the crankcase.

6 indicates the carburetor which supplies mixture to the cylinders thru cross-connection 8, which extends between the manifolds, 10, of the two blocks, one only of which is shown in the figure.

55 A throttle valve, 12, is provided in the intake passages and this is operable by means of suitable links and levers from the driver's compartment. Air is supplied to carburetor 6 thru conduit 14, which is equipped with an 30 air cleaner 16. This cleaner is preferably of the conventional AC type, having means for giving the air a whirling motion so that dust particles are thrown outwardly by centrifugal action and discharged thru slot 18 while 35 the clean air enters passage 20 connected with a conduit, 14.

The crankcase is provided with an outlet, 22, extending into the conduit, 14, and terminating in a nozzle, 24, extending in the 40 direction of air flow. Within the outlet is arranged a flap valve, 26, yieldingly held upon its seat by a light spring, 28, reacting at its other end against plate 30. A cam, 32, carried by shaft, 34, bears against the plate, 30, and when rotated in a clockwise direction forces the plate 30 downwardly increasing the compression of the spring, 28, and thereby more firmly holding valve 26 upon its 45 seat. Shaft 34 is connected by arm 40 and link 42 to the operating lever 13 for the throttle valve 12. This connection is such that as the throttle valve is opened the spring 28 is compressed more and more to hold the flap valve 26 more firmly in closed position.

50 In operation the carburetor receives the major portion of its air supply directly thru cleaner 16 and conduit 14. The suction applied to the conduit, however, likewise affects the nozzle, 24, causing valve 26 to be 55 raised in opposition to the pressure of the spring, 28, resulting in the withdrawal of vapors from the crankcase and their replacement by air entering thru breather 4. As the throttle is opened, cam 32 is rotated to increase the force of spring 28 so that increased suction applied to the nozzle, 24, is met by increasing resistance to opening of the valve, 26. Consequently, there is no increase 60 in flow of vapors from the crankcase at wide 65 70 75 80 85 90 95 100

open position of the throttle. It is apparent that by proper design of the cam 32, any preferred rate of flow may be obtained. That is, the design may be such that flow from the crankcase is entirely cut off at high engine speeds, is greatly reduced or, if preferred, but slightly increased.

I claim:—

1. In an engine including a crankcase having a breather opening, a carburetor provided with an air intake passage, an intake conduit conducting the fuel mixture to the cylinders, a throttle valve in said conduit, a connection between said air intake passage and said crankcase, a valve controlling the flow of vapors thru said connection, a spring urging the valve upon its seat, and means controlled by the position of said throttle valve for varying the tension of the spring so that as the throttle valve is opened, the second named valve is urged more strongly toward its seat.
2. In the combination as defined in claim 1, said last named means comprising a cam rotated by connection with said throttle valve.
3. In an engine including a crankcase having a breather opening, a carburetor provided with an air intake passage, an intake conduit conducting the fuel mixture to the cylinders, a throttle valve in said conduit, a connection between said air intake passage and said crankcase, and means for controlling the flow of vapors thru said connection, said means being connected with the throttle valve for conjoint operation, said means comprising a valve, a spring for yieldingly holding the valve upon its seat and means for adjusting the tension of said spring in accordance with the position of the throttle valve.

In testimony whereof I affix my signature.
DAVID E. ANDERSON.
